UNITED STATES PATENT OFFICE.

WILLIAM X. YORK, OF CLINTON, INDIANA.

ADJUSTABLE WINDOW SHADE AND CURTAIN SUPPORT.

Application filed August 24, 1921. Serial No. 494,880.

To all whom it may concern:

Be it known that I, WILLIAM X. YORK, a citizen of the United States, residing at Clinton, in the county of Vermilion and State of Indiana, have invented certain new and useful Improvements in Adjustable Window Shade and Curtain Supports, of which the following is a specification.

This invention relates to improvements in adjustable window shade and curtain brackets and has as one of its objects to provide a bracket of this class which may be readily and conveniently applied to any ordinary window frame without the use of extraneous fastening means such as screws or nails and which, when applied, will be securely held against displacement.

Another object of the invention is to provide a bracket of the class described so constructed that the members thereof, when spread apart and released, will automatically adapt themselves to the side of the window frame upon which the bracket is to be mounted and will become securely anchored to the said frame, means being provided whereby the members of the bracket may be secured against further separation while the bracket is in use.

Another object of the invention is to provide the bracket with shade roller supports adjustable upon the bracket so as to accommodate and support shade rollers of various lengths, the means for holding the shade roller supports in positions of adjustment serving also as a means for securing the members of the bracket against relative separation after the bracket has been adapted to the window frame.

A further object of the invention is to provide a novel construction of curtain support comprising members resembling in some respects the shade roller supporting members, and an extensible rail extending there between for the direct or indirect support of a curtain or pair of curtains.

In the accompanying drawings:

Figure 1 is a perspective view of the device embodying the present invention.

Figure 2 is a detail perspective view of one of the brackets.

Figure 3 is a group perspective view illustrating the component parts of the bracket shown in Figure 2 disassembled.

Figure 4 is a plan view of one of the brackets, the curtain supporting rail being shown in horizontal section.

Figure 5 is a perspective view illustrating a modified form of the invention.

The bracket embodying the invention is employed in pairs and each bracket comprises a pair of members one indicated in general by the numeral 1 and the other in general by the numeral 2. Both members are preferably formed from sheet metal of a suitable gage, and the number 1 comprises a flat sided oblong rectangular body 3 provided at its upper and lower edges with forwardly projecting flanges 4, and between the flanges with a horizontally extending slot 5 terminating at its ends short of the ends of the body 3. At one end the plate comprising the body 3 is provided with a clamping member 6 which extends rearwardly at right angles with relation to the plane of the body and is provided at its free end with inwardly projecting spurs 7.

The number 2 comprises a body 8 in the form of an oblong rectangular plate formed with a longitudinally extending slot 9 terminating short of its ends, and this body 8 is provided at one end with a clamping member 10 which projects rearwardly at right angles from the plane of the body and is provided at its free end with laterally inwardly projecting spurs 11 corresponding to the spurs 7. In the assembled relation of the parts, the plate 8 is slidably disposed against the forward face of the plate 3 with the slots 5 and 9 in registration at their upper and lower walls and with the said plate 8 received and guided between the flanges 4 upon the plate 3. By a means which will presently be described, the two members 1 and 2 are maintained in the assembled relation stated although the members are capable of relative sliding adjustment so as to provide for relative adjustment of the clamping members 6 and 10 which are located at their relatively remote ends and so that after these members have been separated a suitable distance and the bracket is applied to the side of the window frame, the said clamping members may be brought toward each other so as to clamp the opposite faces of the side of the frame and bring the spurs 7 and 11 into anchoring engagement therewith. In order that the members 1 and 2 may be automatically drawn together so as to cause them to automatically adapt themselves to the side of the window frame against which the bracket is disposed, coil springs 12 are con-

connected at their ends as at 13 to the clamping members 6 and 10 and extend between these members and exert a pull upon the same tending to draw them together. 5 Springs 12 are connected to the clamping members 6 and 10 preferably at points relatively close to the inner corners of these members and therefore relatively close to the juncture of these members with the bodies or plates 3 and 8 respectively. By 10 thus locating the springs 12, the pull exerted thereby is practically in a line with the planes of the plates 3 and 8 and therefore there is a little tendency of the plates 15 to bind either when they are relatively separated against the tension of the springs or relatively drawn together by the pull of the springs.

In connection with each bracket there is 20 provided means for supporting one end of a shade roller, and this means comprises an upstanding bracket arm 14 provided in one instance with a circular opening 15 to receive the round trunnion at one end of 25 the shade roller and in the other instance with a bayonet slot 16 to receive the squared stud of the spring spindle at the other end of the shade roller. The arm 14 is provided at its lower end with a rearwardly right 30 angularly extending supporting portion 17 which in turn is provided with a downwardly extending attaching portion 18 having a forwardly turned lower end 19 and provided between its ends with a preferably 35 rectangularly opening 20. In assembling the bracket arm 14 with the members of the shade bracket, the attaching portion 18 is disposed against the inner or rear side of the body 3 of the member 1 with the portion 40 17 projecting over the upper flange 4 of the body 3 and with the end 19 projecting beneath the lower flange 4 of the said body. A bolt 21 is fitted through the opening 20 and the slots 5 and 9 in the members 1 and 45 2 and is provided with a squared shank portion 22 received within the rectangular opening 20, the bolt being in this manner held against rotation. A wing nut 23 is threaded onto the bolt at the end which projects beyond the face of the member 2, and 50 may be tightened so as to bind firmly against the forward side of the said member 2 and thus clamp the members 1 and 2 together. It will now be evident that the bolt 21 and its nut 23 constitutes not only a means 55 for securing the shade roller bracket arm 14 upon the members 1 and 2 and in the proper position of adjustment longitudinally thereof, but also as a means for securing the members 1 and 2 together in a 60 positive manner so as to preclude their relative separation after they have been once adapted to the side of the window frame.

The brackets also embody means for the 65 support of a curtain and this means com-

prises a bracket arm carried by each bracket and indicated in general by the numeral 24, the bracket arm being provided with a lower attaching portion 25 adapted to be disposed flat against the rear side of the member 1 70 and provided with a forwardly projecting lower end 26 corresponding to the end 19 of the bracket arm 14 and designed to engage in a similar manner beneath the lower flange 4 of the member 1. The attaching 75 portion 25 is provided with a rectangular opening 27 to receive the squared portion of a clamping bolt 28 corresponding to the bolt 21, this bolt 28 projecting through the slots 5 and 9 and having fitted to it a wing nut 29 80 adapted to be tightened and to serve, in connection with the bolt 28, as a means for securing the bracket arm 24 in the proper position of adjustment longitudinally of the members 1 and 2 and also as a means, supplemental to the bolt 21 and nut 23, for securing the said members 1 and 2 against relative separation. The upper portion of the bracket 24 is twisted or otherwise 85 formed as at 30 to provide a forwardly projecting portion 31 to which is telescopically fitted, as clearly shown in Figure 4 of the drawings, the angularly bent end 32 of the respective end member 33 of the curtain supporting rail heretofore referred to. The 90 end members 33 are of flat tubular form and their portions 32 lie at right angles to their body portions, the said portions 32 being as stated telescopically fitted or slipped onto the portions 31 of the bracket arms 24. In 95 addition to the end members 33, the rail comprises an intermediate member 34 in the nature of a bar of suitable dimensions which is telescopically fitted at its ends into the 100 open ends of the body portions of the end members 33 as shown in Figures 1 and 4 of the drawings, it being understood that the rail as a whole is extensible due to the 105 slideable engagement of its ends of the intermediate member 34 in the end members 33, and that therefore the brackets and the connecting rail may be adapted to window frames of various widths. The rail may 110 serve as a direct support for the curtain in which extent the curtain will be provided at its top with a hem slidably receiving the rail, or the curtain may be suspended from rings fitted onto the said rail.

From the foregoing description of the invention 115 it will be understood that the brackets are to be applied by loosening the wing nuts 23 and 29, relatively separating the members 1 and 2, applying the bracket to the face of the window frame, and then releasing the members so as to permit the 120 springs 12 to draw them together and bring their clamping portions 6 and 10 into firm clamping engagement with the opposite faces of the side of the window frame, and their spurs 7 and 11 into biting engagement 125 130

with the frame. After having been thus adapted to the window frame, the bracket may be secured in place by tightening the wing nuts 23 and 29 so as to prevent relative separation of the members 1 and 2 of the bracket. At the time of application of the brackets to the sides of the window frame, and previous to tightening the nuts 23 and 29, the bracket arms 14 and 24 will be suitably adjusted longitudinally of the respective brackets in accordance with the length of the shade roller to be supported and the tastes of the user in draping the curtain about the shade and its roller.

15 In the form of the invention shown in Figure 5 of the drawings, a bracket arm 35 corresponding to the arm 24, is provided at its upper end with spaced forwardly projecting portions 36 and 37 corresponding to the portion 31 of the previously described arm 24 and adapted to have fitted thereto the end members 38 and 39 of rails which correspond to the rails previously described and which are designed to support a curtain and 25 the overdraping therefor, respectively.

Having thus described the invention what is claimed as new is:

1. In a device of the class described, a bracket adapted to be secured to a window frame, said bracket comprising plates assembled for relative sliding adjustment and provided at their relatively remote ends with rearwardly extending clamping members adapted to engage opposed faces on the window frame, springs disposed rearwardly of said plates and extending between the clamping members and connected at their ends at points adjacent the upper and lower edges of said members, and means for securing the plates in position of relative adjustment.

2. In a device of the class described, plates adapted to be secured to a window frame, said plates being assembled for relative sliding adjustment, said plates having arms, adapted to engage opposed faces on the window frame, a space being formed between the window frame and the plates, springs disposed in said space and connecting said arms, said plates having registering longitudinal slots; brackets each having an attaching portion disposed against one of said plates and provided with upper and lower end portions engaging the corresponding sides of said plate, a clamping bolt assembled with the bracket and extending through said slots, a nut threaded upon the bolt and adapted to be tightened to secure the plates in position of relative adjustment and to secure the bracket in adjustment relative to said plates.

3. In a device of the class described adapted to be secured to a window frame, members assembled for relative sliding adjustment and provided with arms adapted

to engage opposed faces on the window frame, a space being formed between the frame and the members, springs in said space connecting said arms, the said members being provided with registering longitudinal slots, brackets each having an attaching portion disposed against one of the said members and provided with upper and lower end portions engaging the upper and lower sides of the said member, a clamping bolt assembled with the bracket and extending through the slots, and a nut threaded upon the bolt and adapted to be tightened to secure the members in positions of relative adjustment and to secure the bracket at adjustment relative to the said members, said brackets being adapted to support a curtain pole.

4. In a device of the class described adapted to be secured to a window frame, members assembled for relative sliding adjustment and provided with arms adapted to engage opposed faces on the window frame, a space being formed between the frame and the members, springs in said space connecting said arms, the said members being provided with registering longitudinal slots, brackets each having an attaching portion disposed against one of the said members and provided with upper and lower end portions engaging the upper and lower sides of the said member, a clamping bolt assembled with the bracket and extending through the slots, and a nut threaded upon the bolt and adapted to be tightened to secure the members in positions of relative adjustment and to secure the bracket at adjustment relative to the said members, said brackets being adapted to support a shade roller.

5. In a device of the class described adapted to be secured to a window frame, members assembled for relative sliding adjustment and provided with arms adapted to engage opposed faces on the window frame, a space being formed between the frame and the members, springs in said space connecting said arms, the said members being provided with registering longitudinal slots, brackets each having an attaching portion disposed against one of the said members and provided with upper and lower end portions engaging the upper and lower sides of the said member, a clamping bolt assembled with the bracket and extending through the slots, and a nut threaded upon the bolt and adapted to be tightened to secure the members in positions of relative adjustment and to secure the bracket at adjustment relative to the said members, said brackets having upward extensions adapted to support shade roller and curtain pole.

In testimony whereof I affix my signature.

WILLIAM X. YORK. [L.S.]
